UNITED STATES PATENT OFFICE.

FRANK E. MODLIN, OF GLENDALE, CALIFORNIA, ASSIGNOR OF ONE-EIGHTH TO FRANK E. MODLIN, JR., OF GLENDALE, CALIFORNIA; ONE-EIGHTH TO CLARENCE A. MODLIN, OF KANSAS CITY, MISSOURI; AND THREE-EIGHTHS TO DAVID L. WALKER, OF OKLAHOMA CITY, OKLAHOMA.

WRAPPING MACHINE.

Application filed March 9, 1926. Serial No. 83,386.

This invention relates to wrapping machines, and to wrapping methods, and more particularly to a machine for wrapping coins to facilitate the handling of coins in 5 banks or elsewhere.

A more particular object is to provide a coin wrapping machine which will be simple in construction, rapid, accurate and efficient in operation, and inexpensive to man- 10 ufacture.

A further object is to provide an improved method of securely wrapping a stack of coins in such manner that the coins at the ends of the stack will be exposed sufficiently 15 to show the denomination thereof.

With the above and other objects in view, the invention consists in the novel and useful provision, formation, combination, association and relative arrangement of parts, 20 members and features, all as hereinafter described, shown in the drawings, and finally pointed out in claims.

In the drawings:

Figure 1 is a side elevation of a machine 25 embodying my invention for wrapping coins;

Figure 2 is a vertical section of the machine shown in Figure 1, taken on the line 2-2 of said figure;

Figure 3 is a transverse vertical section 30 of the coin wrapping mechanism taken on the line 3-3 of Fig. 4, showing the wrapping rollers spread apart to receive a stack of coins;

Figure 4 is a horizontal section taken on line 4-4 of Figure 1, showing the coin 35 wrapping mechanism;

Figure 5 is a horizontal section of the coin wrapping mechanism taken on the line 40 5-5 of Fig. 1;

Figure 6 is a vertical sectional view similar to Fig. 3, but showing the wrapping rollers swung into wrapping position and wrapping a wrapper around a stack of coins, 45 and showing the crimpers in the act of crimping the ends of the wrapper over the edges of the coins;

Figure 7 is a horizontal section, taken on the line 7-7 of Fig. 3 of the wrapping mechanism showing the driving gear for the 50 wrapping rollers and crimpers;

Figure 8 is a fragmentary longitudinal

sectional view of the coin chute and the coin stacking tubes;

Figure 9 is a vertical longitudinal section 55 of the coin chute and one of the coin stacking tubes, taken on the line 9-9 of Fig. 8;

Figure 10 is a sectional view taken on the line 10-10 of Fig. 11, showing the coin 60 chute feed rollers and their driving gear;

Figure 11 is a vertical, longitudinal sectional view of the coin chute feed rollers, taken on the line 11-11 of Fig. 10, showing a portion of the coin hopper and a portion 65 of the coin chute;

Figure 12 is a developed plan view of one of the wrapper blanks;

Figure 13 is an end view of one of the 70 wrappers shown coiled twice in wrapped position; and

Figure 14 is a perspective view of a stack of coins wrapped with one of my wrappers by my machine and method.

Corresponding parts in all the figures are designated by the same reference characters. 75

Referring with particularity to the drawings, I have shown certain devices and elements which may be used with my wrapping mechanism such as a sorting mechanism S, a counting mechanism C and a wrapping 80 mechanism W for each denomination of coins to be wrapped; there being four of such units shown in the present embodiment in Fig. 1, for respectively sorting, counting and wrapping pennies, dimes, nickles and quarters, which units are respectively indicated P, D, N and Q.

Furthermore I have included a coin hopper H, a coin chute I inclined downwardly from said hopper, a coin feed mechanism F 90 between said hopper and said chute, and four coin stacking tubes d, p, n and q, leading vertically downwardly from the chute I to the sorting mechanisms S of the units D, P, N and Q respectively, there being 95 openings d', p', and n' in the bottom of the chute which lead into the upper ends of the tubes d, p and n respectively while the lower end of the chute leads into the upper end of the stacking tube q. The stacking tubes are provided with longitudinal slots d², p², n² and q² for observing the coins in said tubes. The chute I is formed with four superimposed coin guideways 1, 2, 3 and 4

for respectively guiding the dimes, pennies, nickles and quarters into the stacking tubes d , p , n and q . The guideway 1 is of a width to receive only a dime and the bottom 1^a thereof is below the guideways 2, 3, and 4, and the guideway 1 leads downwardly to the opening d' , through which opening dimes are discharged from said guideway into the dime stacking tube d . The guideway 2 is of a width to receive pennies and the supporting faces 2^a thereof are above the bottom 1^a of the guideway 1 and below the guideways 3 and 4, and said faces lead downwardly into the opening p' through 15 which the pennies are discharged from the guideway into the penny stacking tube p . The guideway 3 is of a width to receive nickles and its supporting faces 3^a are above the supporting faces 2^a of penny guideway 2 and the supporting faces 3^a lead downwardly into the opening n' through which the nickles fall from the guideway 3 into the nickle stacking tube n . The guideway 4 is of a width to receive quarters, and its 20 supporting faces 4^a are above the faces 3^a of guideway 3, and the supporting faces 4^a lead downwardly through the lower end of the chute into the quarter stacking tube q into which the quarters drop from the guideway.

The coin feeding mechanism F includes a pair of feed rollers f and f' , and gears 5, 6 and 7 through which said rollers are driven in the same direction. The rollers f and f' are journaled in bearings 8 and 9 at the lower discharge end of the hopper H with the periphery of the roller f flush with the inner side of the rear inclined wall h of said hopper, and with the periphery of the roller f' spaced slightly forwardly from the periphery of the roller f at a distance slightly greater than the thickness of the largest coin handled by the machine, so that the coins may pass between said rollers one by one only. The roller f is mounted outside the hopper with a portion of its periphery projecting through an opening h' in the inclined wall h of the hopper H so that the periphery of said roller rotates flush with the inner side of said wall h . The roller f' is mounted half within the lower end of the hopper and holds all the coins in the hopper except those passing out one by one between the rollers f and f' . The gear 5 is secured on a power shaft 10 between and in mesh with the gears 6 and 7 which are secured on the journals 6' and 7' respectively of the rollers f and f' . The rotation of the gears 6 and 7 by the gear 5 rotates the rollers f and f' both counter clockwise, but the adjacent peripheral surfaces of said rollers within the hopper are rotated in opposite directions so that the peripheral surface of the roller f within the hopper will travel downwardly and feed the coins in the back

of the hopper one by one between the rollers into the chute I, while the peripheral surface of the roller f' within the hopper H travels upwardly and pushes all the coins back into the hopper, except those fed out 70 by the roller f .

The sorting mechanism of each unit comprises a slide s constructed with a lower horizontal plate 11, an upper horizontal plate 12 and a vertical cylindrical sorting barrel B secured at its lower and upper ends to the forward ends of said plates 11 and 12 respectively with the bore of the barrel extending through said plates. The slide s is mounted in a slideway s' which consists of a flat plate 13 with its side edges 14 turned upwardly and inwardly. The slide plate 11 rests and slides upon the slide-way plate 13 with the side edges of the plate 11 fitting and sliding in the channels within the upwardly inturned edges 14 of the plate 13. The slide-way s' is provided with an opening 15 in its forward end. Normally the slide s rests in a position with its barrel B directly under a coin stacking tube such as tube q . (See Fig. 2.) The barrel B is of such height as to hold a predetermined number of coins.

Each counting mechanism comprises a register R with its operating arm r connected to one end of a link 16 which is hooked at its other end into a side slide plate 12 at 16^a.

The wrapping mechanism W comprises primarily a plurality of vertical wrapping rollers w , w' , w^2 and w^3 , spaced apart in a circle, and a pair of crimpers k and k' . The wrapping rollers are preferably made of steel with knurled surfaces 17. The rollers w , w' , w^2 and w^3 have lower journals 20, 21 and 22, and a shaft 23 respectively connected to their lower ends, and said rollers have upper journals 24, 25, 26 and 27 respectively. The lower journals 20 to 22 inclusive, and shaft 23, extend through short radial slots 30 in a lower plate 31, on which plate rest the lower ends of the wrapping rollers w , w' , w^2 and w^3 . An upper plate 32 is fixed on the lower end of a vertical cylindrical throat 33 and a cam disk 34 is journaled on said throat and rests upon the said upper plate. The upper plate 32 is provided with radial slots 35 and the cam disk 34 is provided with a plurality of cam slots 36 which extend over the slots 35 respectively. Each of the upper journals 24 to 27 inclusive, extends upwardly through a pair of slots 35 and 36 in the upper plate and cam disk respectively. The upper end of the throat 33 is fitted in the opening 15 of a slide-way s' . The cam disk 34 is formed with an outwardly extending arm 37, to which is connected one end of a spring 38, the other end of which spring is connected to a stud 39 on the upper plate 32, so that the spring normally holds the cam disk in position with the rear ends of 120

its slots engaging the upper journals 24 to 27 inclusive and holding the upper ends of the wrapping rollers w , w' , w^2 and w^3 in their innermost position. On the lower and 5 upper ends of the wrapping roller w^3 are secured the crimpers k and k' respectively, which consist of metal disks 40 of slightly larger diameter than the roller w^3 , which disks are formed in their crimping faces 10 with a plurality of spaced radial grooves 41. Between the wrapping rollers w^3 and w are located a pair of spaced vertical guides 42 and 43, providing an entrance space 44 there-between through which the coin wrapper is introduced. A guide 45 is located 15 between the rollers w and w' . A guide 46 is located between the rollers w' and w^2 . A guide finger 47 is located between the rollers w^2 and w^3 . A U-shaped wrapper guide 50 20 is provided for guiding the wrapper through the space 44 into the wrapping mechanism. On the lower journals 20, 21 and 22 and on the shaft 23, immediately below the lower plate 31 are respectively secured pinions 51, 52, 53 and 54 which mesh with a gear 55 secured on a sleeve 56 journaled at its upper end in a conical bearing 57 in the lower plate 31. A plunger 58 extends through the sleeve 56 and has a head 59 on its upper end above 25 the plate 31 between the rollers w , w' , w^2 and w^3 . On the lower journals 20, 21 and 22 and on the shaft 23 immediately below the pinions 51, 52, 53 and 54 respectively are secured pulleys 60, 61, 62 and 63 over which 30 extend a coil spring belt 64 which yieldingly holds the lower ends of the rollers w , w' , w^2 and w^3 in their innermost position.

On a power shaft 70 are secured cams 71, 72 and 73 and a bevel gear 74. The bevel gear 74 meshes with a bevel pinion 75 on the lower end of the shaft 23 whereby said shaft is rotated. The cam 71 is engaged by the lower end of a lever 76, the upper end of which is connected to one end of a rod 77 40 which in turn is connected at its other end to the slide s as at 78. The cam 72 is engaged by the lower end of a lever 79, the upper end of which lever engages the cam disk arm 37. The cam 73 is engaged by a 45 lever 80, one end of which engages the lower end of the plunger 58 while its other end is connected to one end of a spring 81 which in turn is connected at its other end to a fixed part 82.

50 The operation is as follows: The coins to be sorted, counted and wrapped are first thrown promiscuously into the hopper H in which they are separated and fed by the feed rollers f and f' one by one into the upper end of the chute I in which the coins travel down their proper slide-ways 1, 2, 3 and 4 into their proper stacking tubes d , p , n and q respectively; the dimes traveling 55 through guide-way 1 and opening d' into stacking tube d ; the pennies traveling through guide-way 2 and opening p' into stacking tube p ; the nickels traveling through guide-way 3 and opening n' into stacking tube n ; and the quarters traveling through guide-way 4 into the stacking tube q . The lowermost coins in the stacking tubes drop into the barrels B of the sorting mechanisms S and fill said barrels with the predetermined number of coins.

The rotation of the cams 71 by shaft 70 75 swings the upper end of the levers 76 forwardly which through links 77 draw the slides s forwardly, separating and sorting the coins in the barrels B from those in the stacking tubes, until the lower end of said barrels coincide with the openings 15 in the sideways s' , whereupon the stacks of coins in said barrels drop through said openings and through the throats 33 into the wrapping mechanisms W between the rollers w , w' , w^2 and w^3 onto the plunger head 59; the upper ends of said rollers at this time having been spread apart to receive the coins, by the engagement of the cam slots 36 with the upper journals 24 to 27 inclusive of said 85 rollers, with the turning of the cam disk 34 by the engagement of the lever 79 with the disk arm 37 upon the swinging of said lever by the cam 72. When the slide barrels B are moved from under the stacking tubes d , p , n and q , the upper plates 12 of the slides 3 pass under the lower ends of said tubes and support the stacks of coins therein, until the slides return to normal position and their barrels B again rest under the stacking tubes, whereupon a predetermined number of the lowermost coins in said tubes again drop into said barrels for the next sorting operation. Each time a slide s is moved forwardly and the stack of coins 100 dropped from its barrel, the counting mechanism is operated by the link 16 and one stack is registered on the register R.

As soon as the coins drop into the wrapping mechanisms W the levers 79 are swung 110 by the cams 72 backwardly and the springs 38 turn the cam disks 34 clockwise; whereupon the cam grooves 36 engaging the upper journals 24 to 27 inclusive swing the upper ends of the rollers w , w' , w^2 and w^3 inwardly 115 against the coin stack therebetween, while the lower ends of the rollers are drawn against the coin stack by the spring belt 64, thus holding the roller vertical in parallel relation against the coins and stacking the 120 coins in perfect alignment within the wrapping mechanism W. In this position of the rollers the edges of the crimpers K and K' extend respectively under the edge of the lowermost coin and over the edge of the uppermost coin in the stack of coins in the wrapping mechanism. The roller w^3 , crimpers K and K', and pinion 54 are rotated 125 clockwise by the power shaft 70 through the bevel gears 74 and 75 and shaft 23, while 130

the rollers w , w' and w^2 are rotated clockwise by pinion 54 through gear 55, pinions 51, 52 and 53 respectively and lower journals 20, 21 and 22 respectively. A wrapper 5 W' is then fed through the guide 50 and space 44, between the rotating rollers w , w' , w^2 and w^3 and the stack of coins surrounded by the rollers, whereupon the wrapper is rolled twice around the stack of coins in two 10 coils (see Fig. 13) while the lower and upper edges of the wrapper are respectively crimped by the crimpers K and K', a short distance over the lower face of the lowermost coin in the stack, and a short distance over the upper face of the uppermost coin in the stack, leaving a sufficient area of said faces of said coins exposed so that the denomination of the coins may be seen and read (see Figs. 6 and 14). The rollers w , w' , w^2 and w^3 are then spread apart by the cam 72, through lever 79, cam disk arm 37, disk 34 and cam slots 36, and journals 24 to 27 inclusive. The plunger 58 is then elevated by the cam 73 through lever 80 and 20 the wrapped stack of coins is elevated out of the wrapping mechanism W through throat 33 as shown in dotted lines in Fig. 6.

It is obvious that various changes and 30 modifications may be made in practicing the invention, in departure from the particular showing of the drawing, without departing from the true spirit of the invention.

Having thus disclosed my invention, I 35 claim and desire to secure by Letters Patent:

1. In a machine of the character described, a wrapping mechanism comprising a plurality of wrapping rollers, a pair of crimpers at the lower and upper ends respectively of one of said rollers, a plunger between the lower ends of said rollers, means whereby a stack of coins may be introduced between said rollers onto said plunger, means whereby a wrapper may be introduced between the stack of coins and one of said rollers, and means for rotating said rollers and crimpers to roll the wrapper around the stack and to crimp the ends of the wrapper over the end coins of the stack, and means for elevating said plunger to eject the wrapped stack of coins from the wrapping mechanism.

2. In a machine of the character described, a wrapping mechanism comprising a lower plate and an upper plate, said plates being provided with a plurality of slots, a plurality of wrapping rollers, journals on the lower ends and on the upper ends of said rollers, said lower journals extending through the slots in the lower plate and said upper journals extending the slots in the upper plate, a pair of crimpers on the lower and upper ends respectively, pulleys on said lower journals, a spring belt extending over said pulleys and yieldingly holding the lower ends of the rollers in their innermost position, a cam disk on the upper plate provided with cam slots through which the upper roller journals extend so that by turning the disk said slots will engage said journals to spread or bring together the upper ends of said rollers.

lower ends of the rollers in their innermost position, a cam disk on the upper plate provided with cam slots through which the upper roller journals extend so that by turning the disk said slot will engage said journals to spread or bring together the upper ends of said rollers, a throat extending through said disk and said upper plate through which a stack of coins may be introduced between the spread rollers, the 70 rollers being brought against the stack of coins by said cam, said rollers and said stack being adapted to have a wrapper introduced therebetween, means for rotating said rollers to roll the wrapper around the 75 stack of coins and for causing the crimpers to crimp the ends of the wrapper over the end coins of the stack, and means for ejecting the wrapped stack of coins from between the rollers when spread apart by said cam. 80 85

3. In a machine of the character described, a wrapping mechanism comprising a plurality of wrapping rollers, a pair of crimpers at the lower and upper ends respectively of one of said rollers, a plunger between the lower ends of said rollers, means whereby a stack of coins may be introduced between said rollers onto said plunger, means whereby a wrapper may be introduced between the stack of coins and one of said rollers, and means for rotating said rollers and crimpers to roll the wrapper around the stack and to crimp the ends of the wrapper over the end coins of the stack. 90 95

4. In a machine of the character described, a wrapping mechanism comprising a lower plate and an upper plate, said plates being provided with a plurality of slots, a plurality of wrapping rollers, journals on the lower ends and on the upper ends of said 100 rollers, said lower journals extending through the slots in the lower plate and said upper journals extending the slots in the upper plate, a pair of crimpers on the lower and upper ends respectively of one of said 105 rollers, pulleys on said lower journals, a spring belt extending over said pulleys and yieldingly holding the lower ends of the rollers in their innermost position, a cam disk on the upper plate provided with cam 110 slots through which the upper roller journals extend so that by turning the disk said slots will engage said journals to spread or bring together the upper ends of said rollers. 115

5. A machine of the character described, a wrapping mechanism comprising a plurality of wrapping rollers, a pair of crimpers at the lower and upper ends respectively of one of said rollers, means whereby a stack of coins may be introduced between said rollers, means whereby a wrapper may be introduced between the stack of coins and one of said rollers, means for rotating said rollers and pair of crimpers to roll the 120 125 wrapper around the stack and to crimp the 130

ends of the wrapper over the end coins of the stack, and means for releasing said rollers from said stack of coins when so wrapped.

- 5 6. A machine of the character described, a wrapping mechanism comprising a plurality of wrapping rollers, a pair of crimpers at the lower and upper ends respectively of one of said rollers, means whereby a stack 40 of coins may be introduced between said rollers, means whereby a wrapper may be introduced between the stack of coins and one of said rollers, means for rotating said rollers and pair of crimpers to roll the wrap- 45
10 per around the stack and to crimp the ends of the wrapper over the end coins of the stack, means for releasing said rollers from said stack of coins when so wrapped, and means for ejecting the wrapped stack of 50 20 coins from between the rollers when released, therefrom.

7. In a machine of the character described, a wrapping mechanism comprising a plurality of wrapping rollers, a pair of crimpers at 25 the lower and upper ends respectively of one of said rollers, shafts for said rollers, a cam for engagement with the upper ends of said shafts, and normally spreading the rollers apart, and means for operating the 30 said cam to position the rollers in substantial parallelism.

8. In a machine of the character disclosed, a wrapping mechanism comprising a lower 35 plate and an upper plate, said plates being slotted, wrapping rollers, shafts passed

through said rollers, said shafts being received in the slots of the lower and upper plates, upper and lower crimpers on one of said rollers, means yieldingly holding the lower end of said shafts in their innermost position within the slots of the lower plate, and cam means for engagement with the upper ends of said shafts to spread said shafts apart or to position the said rollers in substantial parallelism. 45

9. In a machine of the character disclosed, a wrapping mechanism comprising a lower plate and an upper plate, said plates being slotted, wrapping rollers, shafts passed through said rollers, said shafts being received in the slots of the lower and upper plates, upper and lower crimpers on one of said rollers, means yieldingly holding the lower end of said shafts in their innermost position within the slots of the lower plate, and cam means for engagement with the upper ends of said shafts to spread said shafts apart or to position the said rollers in substantial parallelism; means whereby a stack of coins may be introduced between 50 55 said rollers when spread apart, means whereby a wrapper may be introduced between the stack of coins and one of said rollers, and means for rotating said rollers and crimpers to roll the wrapper around the stack of coins 60 and to crimp the ends of the wrapper over the end coins of the stack. 65

In testimony whereof, I have signed my name to this specification.

FRANK E. MODLIN.
